UNITED STATES PATENT OFFICE.

GEORGE C. GARDNER, OF CHICAGO, ILLINOIS.

DESIGN FOR A WHEEL.

SPECIFICATION forming part of Design No. 33,975, dated January 22, 1901.

Application filed December 24, 1900. Serial No. 40,979. Term of patent 7 years.

To all whom it may concern:

Be it known that I, GEORGE C. GARDNER, a citizen of the United States of America, residing at Chicago, in the county of Cook and State of Illinois, have invented and produced a certain new and original Design for Wheels, of which the following is a specification.

The drawings represent the design by means of a side view in Figure 1 and a diametrical section in Fig. 2.

Referring to the drawings, A is an annular portion divided toward the center into two oppositely-extending flanges $a a'$ of substantially even thickness and having an inwardly-

circular shape in diametrical section, as seen 15 in Fig. 2.

The essential portion of my design I consider to be the inwardly-circular flanges $a a'$ of substantially even thickness.

I claim as new and desire to secure by Letters Patent—

The design for a wheel, substantially as shown and described.

GEORGE C. GARDNER.
